Primary Examiner—Melanie H Tung*Assistant Examiner*—Susan Moon Lee(74) *Attorney, Agent, or Firm*—Daniel V. Thompson(57) **CLAIM**

The ornamental design for a collapsible travel pet bowl, as shown and described.

DESCRIPTION

FIG. 1 is an enlarged perspective view of a collapsible travel pet bowl showing my new design;

FIG. 2 is a bottom plan view thereof;

FIG. 3 is a top plan view thereof;

FIG. 4 is a front elevational view thereof; and,

FIG. 5 is a right side elevational view thereof.

The collapsible travel pet bowl of the present invention is symmetrical so that the front and rear views are identical as are both side views.
